PAGE 2

Fig. 2

Fig. 3

Fig. 5

FIG. 1 is a right side elevational view of a house trailer embodying my new design;

FIG. 2 is a left side elevational view thereof;

FIG. 3 is a front elevational view thereof;

FIG. 4 is a rear elevational view thereof; and

FIG. 5 is a perspective view showing the top and one side.

The dominant feature of my design resides in the portions shown in full lines.

I claim:

The ornamental design for a house trailer, as shown and described.
